(57) CLAIM

The ornamental design for a vehicle body, as shown and described.

DESCRIPTION

FIG. 1 is a right side view of a vehicle body showing my design and is a mirror image of the left side thereof;

FIG. 2 is a front view thereof;

FIG. 3 is a rear view thereof; and,

FIG. 4 is a top view thereof.

The wheels shown in broken lines in FIG. 1 are for illustrative purposes only and form no part of the claimed design.

1 Claim, 2 Drawing Sheets

FIG. 4
